UNITED STATES PATENT OFFICE.

BENTON C. ROWELL, OF CHICAGO, ILLINOIS; LILLA C. ROWELL EXECUTRIX OF SAID
BENTON C. ROWELL, DECEASED.

TRAIN INSTRUMENT FOR SIGNAL SYSTEMS.

1,193,470.

Specification of Letters Patent.

Patented Aug. 1, 1916.

Application filed September 1, 1910. Serial No. 579,978.

To all whom it may concern:

Be it known that I, BENTON C. ROWELL, a citizen of the United States, residing in Chicago, in the county of Cook and State of Illinois, have invented a new and useful Improvement in Train Instruments for Signal Systems, of which the following is a specification.

This invention relates to the construction of what are known as train instruments adapted to be carried on locomotives and to cause the setting of the brakes when they encounter coöperating instruments on the track. A type of train instrument is shown in my Patent, No. 776146, dated November 29, 1904, and the present invention is an improvement upon the patented construction.

The nature of my improvement is fully disclosed in the following description, and it is also illustrated in the accompanying drawing, in which—

Figure 1 is a sectional elevation on the line 1—1 of Fig. 2, and Fig. 2 is a front elevation of the instrument, the front plates being omitted. Fig. 3 is a detail view of the lever used in returning the device to normal. Fig. 4 is a plan view of the lever for holding the valve closed. Figs. 5 and 6 are partial, sectional elevations, one showing the controlling valve closed and the other showing it open. Figs. 7 and 8 are enlarged perspective views of the devices for locking the slide controlling the valve, one showing them in the locking position and the other showing them in the unlocking position. Figs. 9 and 10 are detail views of one of said locking devices.

In said drawing, 10 represents the connection to the air pipe of the train brake, and under it I provide a well or trap 11 adapted to collect condensations from the train pipe, and from which it is drawn off whenever necessary by the cock 12. The air passes through the trap over the top of the partition 13 and into the valve chamber 14, in the bottom of which is seated the controlling valve 15, preferably adapted to open downward, and having a strong spring 16 surrounding its stem and pressing upward against the shoulder 17 on the stem. A washer 18 supports the spring at the bottom and is adapted to move vertically a limited distance on the stem, and it serves as a means of compressing the spring as de-

scribed later on. Below the washer 18 is a sleeve 19 surrounding the stem and made fast thereon by a screw thread and a pin 20, and acting to limit the downward movements of the washer.

The valve is held closed by a lever 21 swinging on a shaft or pivot 22 and having its end forked with one limb on each side of the stem and in position to support the washer 18. The opposite end of the lever 21 is also forked, and the limbs of such end each extend on opposite sides of the neck 23 at the upper end of a sliding plate 24 adapted to be lifted by any track instrument over which the train may pass and which may at the time of passing be in the danger position. The neck 23 is topped by a head 25 and the limbs of the lever engage this head. In its normal position with the controlling valve closed, the lever 21 stands horizontal, as seen in Fig. 5, and the spring 26 is compressed, but when the valve is open, the end under the valve is depressed and the spring is expanded, as in Fig. 6.

Adjacent to the plate 24 is a locking plate 26 adapted to be lifted by the track instrument slightly in advance of plate 24. This plate 26 normally locks plate 24 against any movement whatever. To obtain the advance movement, its bottom is extended a short distance below that of plate 24, as seen at Figs. 1, 2 and 5, so that it will be lifted before plate 24, and through this advance movement, plate 24 is released so that it is enabled to rise when actuated by the track instrument, a portion 27 of which is shown as lifting both the plates in Fig. 6. The locking of plate 24 is effected by two oppositely swinging dogs 28 pivoted on the upper horizontal members of U shaped retainers, the heads of which are upset one against plate 24 and the other end against the face of projection 31 of dog 28. The dogs when locked engage shoulders 29 on the edges of the inclosing frame or boxing 30, and they are released by laterally extending projections 31 formed upon the backs of the dogs and positioned so that they enter openings 32 in the plate 26. These openings are shaped so that they act as cams when the plate 26 rises and swing the dogs out from their engagement with shoulders 29, thus releasing the plate 24 from its lock, and allowing it to be lifted by the track instru-

ment from the position of Fig. 5 to that of Fig. 6. When the plate 24 is released, the head 25 moves upward with the plate and allows the lever 21 to swing to the position of Fig. 6 so that spring 16 expands until the washer 18 rests on the sleeve 19 and the lever is arrested by the shoulders 40 upon the resetting pin hereinafter mentioned. The washer in this position prevents any further expansion of spring 16, but the movement is sufficient to enable the air pressure upon the valve to force it open and vent the train pipe.

The plate 26 is provided with downwardly acting springs 33 encircling spindles 42 upon the top of the plate and confined between the plate and a stationary cross member 34 of the instrument, through which the spindles are free to slide. These springs are constantly pressing the plate 26 downward, and consequently after the track instrument is passed, they are adapted to return the plates to normal position again as soon as the spring 16 is again compressed as in Fig. 5. In recompressing said spring, the lever 21 is moved back from the position of Fig. 6 to that of Fig. 5, and the operation is a manual one performed with the aid of a bar or lever 35, the end of which is inserted in the notch 36 upon the front plate 37 of the inclosing box, which plate is adapted to be secured by studs 38. The bar 35 fulcrumed in the notch 36 is adapted to set under a resetting pin 39, and when the bar is raised, it lifts the pin which is freely hung in an opening in the cross member 34. The pin is provided with side flanges or shoulders 40 which lie under and are adapted to engage the limbs of lever 21 when the pin is raised by the bar. In this manner, the lever 21 is restored to its horizontal position and at the same time the spring 16 is again compressed so that the train instrument is again ready for service. As a matter of safety to the resetting pin, I provide downwardly extending guards 41 at each side of it and attached to said cross member 34.

It will be noted that the valve when opened to the extent necessary to vent the brake pipes is only moved a limited distance, so that the valve is adapted to be closed by the pressure of springs 33 and the weight of slides 24 and 26 as soon as the pressure in the pipes has been reduced below their combined power, thereby preventing the complete exhaustion of the pipes. The combined power of springs 33 and slides 24 and 26 can be such as to close the valve against any desired pressure, but must always be less than that required to reset spring 16. As spring 16 must be compressed to allow slides 24 and 26 to drop sufficiently to allow lock dogs 28 to engage the shoulders 29, the valve after venting the pipe becomes a balanced valve holding a predetermined pressure in

the train pipe and refusing to hold a greater pressure until spring 16 is compressed and slide 24 locked by the use of hand lever 35.

I claim:

1. A train instrument adapted to coöperate with a track instrument and comprising a valve controlling the air brakes of the train, a device acting against the pressure of air for holding the valve closed, a slide controlling said holding device, means for locking the slide, and means for releasing the slide. 70

2. A train instrument adapted to coöperate with a track instrument and comprising a valve controlling the air brakes of the train held to its seat against the pressure of said air, a rocking device for holding the valve closed, a slide controlling said holding device, means for locking the slide, and means for releasing the slide. 80

3. A train instrument adapted to coöperate with a track instrument and comprising a valve controlling the air brakes of the train, a device acting against the pressure of air for holding the valve closed, a slide acting to control said holding device, means for locking said slide, and means for releasing the slide. 85

4. A train instrument adapted to coöperate with a track instrument and comprising a valve controlling the air brakes of the train, a device acting against the pressure of air for holding the valve closed, a slide controlling said holding device, movable dogs for locking said slide, and a second 95 slide for releasing said dogs. 100

5. A train instrument adapted to coöperate with a track instrument and comprising a valve controlling the air brakes of the train, a device acting against the pressure of air for holding the valve closed, a slide controlling said holding device, movable dogs for locking said slide, and a second slide for releasing said dogs, said slides being one in advance of the other. 110

6. The combination in a train instrument, of a valve controlling the air brakes, a spring pressing upon the valve, a positively acting device for normally holding the valve closed and said spring compressed, and extraneous means whereby said holding device may be made to restore the compression in the spring after the train pipe has been vented, and the compression in said spring reduced. 115

7. A train instrument having a valve controlling the air-brake pipe and closing against its pressure, means yieldingly holding said valve in closed position, and closing means operable with variable pressure upon said yielding means for closing said valve 120 after pressure in the air pipe has been reduced, said closing means maintaining said valve closed when the train pipe is both in vented and normal conditions. 125

8. A train instrument having a valve con- 130

trolling the air brake pipe, yielding means for closing said valve against the pressure of air in the air brake pipe, said means having insufficient strength to close said valve against the normal pressure in said air brake pipe and yet having sufficient strength to close said air brake pipe after the pressure has been reduced and before it is exhausted,

and manually operable means for closing said valve and means for locking it in closed position.
